UNITED STATES PATENT OFFICE.

FRANZ FLEISCHMANN, OF KLAGENFURT, AUSTRIA-HUNGARY.

TEMPORARY CLAMP FOR ARTIFICIAL SLATES OR TILES.

1,173,499.

Specification of Letters Patent. Patented Feb. 29, 1916.

Application filed August 17, 1915. Serial No. 45,874.

To all whom it may concern:

Be it known that I, FRANZ FLEISCHMANN, a subject of the Emperor of Austria-Hungary, residing at 2 Wulfengasse, Klagenfurt, 5 Corinthia, Austria-Hungary, have invented certain new and useful Improvements in Temporary Clamps for Artificial Slates or Tiles, of which the following is a specification.

10 It is known that artificial slate-tiles warp under the influence of the sun, so that they must be held down by so-called storm-clamps. These consist of a nail preferably made of copper, the broad head of which is 15 inserted below the butt-joint of two adjoining tiles, in such a manner that the pin of the nail projects through the joint upwardly and engages a hole, the so-called storm-clamp-hole, of a third plate which overlaps 20 the two plates, whereafter the said nail is bent over, so that all three plates are pressed together by this storm-clamp. Through these storm-clamp holes, however, which lessen the covering capacity of the tiles, the 25 rainwater may enter, and if the rain lasts long, will pour through the roof.

According to this invention, this drawback is avoided by an arc-shaped (or U-shaped) clamp, the lower leg of which is 30 equipped with lateral, flat extensions and with a bent broadened end, so that the adjoining tiles which are superposed upon the flat projections, are clamped together with the overlapping tile which is inserted into the clamp without any necessity of perforating the tiles.

The flat projections of the clamp may form an integral bent part of the clamp, or it may consist of a plate connected with the 40 clamp. Further, the clamps may stay permanently in the roof, or be removed after the seasoning of the roofing.

In the drawing the subject of the invention is shown in several modifications.

45 Figure 1 is a front view showing the device together with the clamped tiles in the ordinary style of roofing. Fig. 2, a section on line A—A of Fig. 1. Fig. 3, a section on line B—B of Fig. 1. Figs. 4 and 5 show other 50 modifications of the clamp. Fig. 6 shows another modification of the clamp seen from the top, the tiles being laid in the German style. Fig. 7 is the corresponding side-view. Fig. 8 shows a front view clamp connected 55 with a metal plate and used in the ordinary

style of roofing. Fig. 9, a section of line C—C of Fig. 8. Fig. 10, a section on line D—D of Fig. 8. Figs. 11 to 14 show other modified forms of clamp. Fig. 15 shows a second form of the clamp used with the tiles laid in 60 the German style. Figs. 16 to 18 show modifications of a clamp made of sheet iron or tin plate.

The improved device for fastening the tiles on roofs generally consist of a springy 65 clamp with two unequal legs 1, 2 made of steel-wire (Figs. 1 to 7), the longer leg 1 being bent out and flattened in a plane at right angles to the plane of the short leg 2 of the clamp. As shown in Figs. 1 to 3, 70 75 the leg 1 may be bent to one side or, as Fig. 4 shows, it may be formed like an S. In the latter case an enlargement 4' may be provided for. In Fig. 5 another modification of the clamp is shown, where there are two lateral portions constituting the longer leg, such portions being bent in opposite directions so that the clamp is heart-shaped.

The shorter leg 2 of the clamp is, in all 80 modifications, bent with its free end toward the other leg 1 either directly or with an intermediate coil forming a spring between the two legs.

The end 1' of the other flattened leg 1 is 85 bent out forwardly and suitably thickened (see Fig. 1). The bent part 4 may be continued, as shown in Fig. 1, and form a further flat part 5, or it may form a hook 6 (see Fig. 4) extending over both sides. According to Fig. 5 each leg 1' is bent at its 90 end to form a hook 7 pointing in opposite directions.

In Figs. 6 and 7 a clamp is shown which is similar to the clamp shown in Figs. 1 to 3, with the difference that the flattened leg 95 1 is considerably longer than the leg 2.

In Figs. 8 to 12 other modifications of clamps are shown, in which the wire is formed into a resilient clamp having unequal legs 1, 2, the lower and longer leg 1 having a plate 8 connected thereto which forms the flat, lateral extensions and which is made of tin-plate or sheet iron. This plate is formed with a longitudinal groove 9 into which is laid the leg 1, the latter being fastened by 100 bent parts 9' of the said plate.

The free end 1' of the clamp leg is normally bent either toward the left hand (see Figs. 8 to 10) or toward the right hand, or it may be bent so that it forms, at right 110

angles to the plane of the wire-clamp 2, a hook 10 (see Fig. 11) or a loop (see Fig. 12). In the modifications shown in Figs. 8 to 12 the plate 8 is provided on one side with a projection 12 on which the broadened end of the leg 1 rests, whereby the tilting of the clamp-leg to this side is prevented.

In the clamp shown in Fig. 15 the leg 1 is considerably longer than the plate 8, so that 10 its end can not bear upon the plate 8 and therefore, in this modification, the projection 12 of the plate is omitted. The free end of the leg 1 of the clamp shown in Fig. 15 is bent to the right side, but, as shown in 15 Figs. 8-12, it can also be bent to the left side, or it can be widened to form a hook or an ear.

According to Figs. 13 and 14 the end 13 of the leg 1 is bent in opposite direction to 20 leg 2; that is to say downwardly, and it is pointed at its free end thereby forming a nail which is to be driven into the wood-work of the roof.

In Figs. 16-18 two other modifications of 25 clamps are shown, which are made of a single piece of tin-plate or sheet iron. In the clamp shown in Fig. 16 the plate 8, which has a longitudinal groove 9 and which forms the lower leg 1 of the clamp, is formed with 30 a hook 23 in alinement with the groove 9, which hook may be bent either to the right or to the left hand side. The clamp shown in Fig. 17 has this hook 23 and in addition an upwardly projecting integral part 24 of 35 the plate 8, such part 24 being on the opposite side of hook 23 from the groove 9. In Fig. 18 the hook 23 is omitted, and on both sides of the groove projections 24, extending upwardly, are arranged. In the modification 40 of the clamp shown in Figs. 16 and 18 the springy short leg 2 is made of the material of the end of the plate 8 opposite to the end provided with the hook 23 and projections 24, respectively. In this case the 45 upper leg 1 may form a triangle (Fig. 16) or, as shown in Figs. 17 and 18, it may consist of two pointed projections 25 which are either parallel (see Fig. 17) or bent toward each other (see Fig. 18).

50 In Figs. 1, 2, 3 and 8-10 the application of the clamp to ordinary style roofing is shown, and in Figs. 6, 7 and 15 to the so-called German style roofing. The application of the clamp is effected as follows: As 55 evident from Figs. 1 to 5 and 8 to 10 the clamp is laid with its flat part 1, or projections 8, upon the lower roofing tile 14, in such a manner that the resilient leg 2 is on top. Two other tiles 15, 16 are then placed 60 on both sides of the clamp, the edges of which are provided, at the point adjacent the end or ends of the leg 1, with recesses 17, while such edges otherwise adjoin each other to form a butt-joint 18. By means of 65 the recesses 17 the respective location of the

two tiles is determined, so that the clamp also serves for controlling the correct overlapping of the tiles.

In the S-shaped clamp shown in Fig. 4, the recesses are not only provided at the point of the hook shaped end, but also at the thicker part 4 of the middle of the clamp. 70

When using the clamps shown in Figs. 8 to 15 and 16 to 18 the adjoining edges of 75 the tiles 15 and 16 must be spaced apart adjacent the plate 8, so as to make room for the part constituting the longitudinal groove 9.

In the device shown in Fig. 15 the spacing 80 must be such as to leave room for the whole length of the leg 1.

The recesses 17 of the plates may be made either in the manufacturing process or cut 85 with a chisel or the like when the tiles are being mounted. Into the recess or recesses 17 the bent or thickened part 1' or 4 (Figs. 1, 6 and 8) or the hook 6, 10, 23 (Figs. 4, 11, 16 and 17) or the ear 11 (Fig. 12) or the 90 projections 24 of the clamp (Figs. 17, 18) is laid, and thereby the clamp is secured in position in relation to the two tiles 15, 16. The covering tile 22 is then inserted into the clamp, so that it be located under the leg 2. 95

The leg 2, which is springy, or is pressed downwardly after the insertion of the tile 22, presses the latter against the lower tiles 15, 16, clamping all three plates 15, 16 and 22 together by one clamp and avoiding un- 100 covered holes.

In the case of the clamps shown in Figs. 6, 7 and 15, which are particularly used in the German style of roofing, the recessing or cutting of the tiles is avoided, as the leg 1 is so long that its end grips and holds the upper edge of the tile. 105

As soon as the tiles are completely hardened and dried, so that they will warp no more, the clamps shown in Figs. 8 to 10 and 15 can be removed after the upper leg 2 has been loosened and they can be used over again, while the other clamps are designed to stay in the roof. 110

What I claim is:

1. A clamp, for temporarily pressing upon the lower portions of two substantially abutting artificial tiles which have their top edges secured to the framing of the roof and the adjacent edges of which are covered by the lower part of another tile also having its top edge secured to the framing of the roof, comprising a springy pincer-shaped member having a flat lower leg shaped to extend below both of the substantially abutting tiles and adapted to be suspended from at least one of the tiles. 120

2. A clamp, for temporarily pressing upon the lower portions of two substantially abutting artificial tiles which have their top 125

edges secured to the framing of the roof and which are covered by the lower part of another tile also having its top edge secured to the framing of the roof, comprising a springy pincer-shaped member having a flat lower leg shaped to extend below both of the substantially abutting tiles and provided with a projection in a position where it is caused, by the action of gravity, 10 to bear against the top edges of at least one of the tiles.

3. A clamp, for temporarily pressing upon the lower portions of two substantially abutting artificial tiles which have their top 15 edges secured to the framing of the roof and the adjacent edges of which are covered by the lower part of another tile also having its top edge secured to the framing of the roof, comprising a springy pincer-shaped member having a flat lower leg shaped to extend below both of the substantially abutting tiles and provided with a projection in a position to engage a recess 20 in at least one of the tiles.

25 4. A clamp, for temporarily pressing upon the lower portions of two substantially abut-

ting artificial tiles which have their top edges secured to the framing of the roof and the adjacent edges of which are covered by the lower part of another tile also having 30 its top edge secured to the framing of the roof, comprising a springy, pincer-shaped member, formed of wire, having a flat lower leg shaped to extend below both of the substantially abutting tiles and provided with 35 at least one projection to engage a corresponding recess in the tiles.

5. A clamp for temporarily pressing together the lower portions of two superposed layers of artificial roof tiles the top portions 40 of which are secured to the roof, comprising a springy hinge-joint, a fingerlike upper jaw, a flat lower jaw and means for suspending the clamp from at least one tile.

In testimony whereof I have signed my 45 name to this specification in the presence of two subscribing witnesses.

FRANZ FLEISCHMANN.
